UNITED STATES PATENT OFFICE.

FREDERICK GETTELMAN, OF MILWAUKEE, WISCONSIN.

SAFETY-GAGE FOR LIQUIDS.

1,027,721.

Specification of Letters Patent. Patented May 28, 1912.

Application filed December 11, 1909. Serial No. 532,656.

To all whom it may concern:

Be it known that I, FREDERICK GETTELMAN, a citizen of the United States, and resident of Milwaukee, in the county of Milwaukee and State of Wisconsin, have invented certain new and useful Improvements in Safety-Gages for Liquids; and I do hereby declare that the following is a full, clear, and exact description thereof.

10 The object of my invention is to provide a safety device especially applicable to feed water for boilers, its arrangement and construction being such that a permanent record is made whereby the height of the water 15 in a receptacle or boiler is indicated and thus shows at a glance the variation in said water height for a given period of time. The invention therefore consists in certain 20 peculiarities of construction and combination of parts to be set forth hereinafter with reference to the accompanying drawings and subsequently claimed.

In the drawings Figure 1 shows a sectional elevation of a device embodying the 25 features of my invention, being a combined float and recording gage, and Fig. 2, a detail cross-section as indicated by line 2—2 of Fig. 1.

Referring by characters to the drawings 30 1 indicates a two-part steam-tight float-casing the body portion of which is in the form of a cylindrical well having a water inlet-pipe 2, which pipe is connected to a boiler or other liquid receptacle. There is also connected to the float casing at its top an equalizing pipe 3, the same being connected to the boiler or receptacle above its water line, by which arrangement a uniform water level 35 in the boiler is maintained in said float casing, the water level therein being visibly indicated by the usual gage 4 connected above and below the maximum and minimum water levels. The upper well portion of the casing is provided with a laterally 40 extended chamber 5, and in the outer end of this chamber is mounted a spindle 6, having a conical end fitted in a conical recess to form one of its bearings, while the opposite end of said spindle projects through the 45 chamber and has its bearing in a stuffing box 7. The spindle 6 within the chamber carries a lever 8, which extends into the casing proper and has pivotally secured to its end a suitable float 9. As shown in Fig. 1 50 of the drawings, the float is preferably provided with spring-guards 10, the free ends

of which guards are recurved and serve to engage the adjacent sides of the casing to hold and guide the float in its travel in an approximately central position relative to 60 the walls of the well portion of said casing.

By utilizing a guided float in shackle or hinge connection with the lever 8 as described, it is apparent that said float is capable of direct vertical movement whereby 65 a uniform thrust is applied to the end of said lever when the float rises and this construction permits of great float area with a minimum casing area resulting in economy 70 of construction as well as insuring sufficient volume of water under the float to cause the same to respond quickly when power is required to actuate the device.

A short arm 11 is secured to the end of the spindle exterior of the chamber and this 75 short arm is provided with a pin extension, which is adapted to engage the forked end 12 of an oscillatory stylus lever 13. The lever 13 is fulcrumed to an ear 14, which ear extends from a gage-casing 15 that is secured to the walls of the chamber 5. The gage-casing is provided with a suitable gear-train 16 as indicated by dotted lines in Fig. 1, and a spring or weight motor, not shown. A central shaft 17 of the gage mechanism 80 carries the usual circular index card 18, which card is revolved by a motor in any suitable manner. The details of the gage mechanism are immaterial to my invention, and it should be understood that any motor-driven indicator card may be utilized, having a lever and stylus pen, or other suitable marking device attached to its free end for recording variations of the water level upon the indicator card, which card is adapted to 85 travel at approximately a right angle to movement of the stylus.

From the foregoing description it will be understood that should the water level rise in the boiler or receptacle, the water contained in the well portion of the float casing will have a corresponding movement. As shown in Fig. 1, the water level is at its lowest point and the lever 13, which is connected to lever 8, is therefore at the zero 90 point on the card. Now, should the water rise in the boiler and casing, the float 9 will cause lever 8 to move upward, assuming a position corresponding to the height of the rise of the water. The movement of the end 95 of the stylus lever 13 will thereby describe an arc of a circle outwardly from the center 100 105 110

of the card and, owing to the fact that the card is also being slowly rotated by the motor, the exact height or elevation of the water will be marked upon said card, which 5 card is provided with the usual scaled lines arbitrarily indicating various heights of the water level. Should the level of the water fall, this action is repeated, and so on throughout the twenty-four hours of a day, 10 the card will continually register and permanently indicate the various water levels in a positive manner.

The safety of this device is apparent when it is taken into consideration that, even 15 though the water glass 4 would show a maximum height of water therein, this height may not under all conditions correspond to the water level height within the boiler and casing, due to the fact that 20 slight deposits of mud or foreign matter, have been known to choke the inlet communication between the water gage and casing, and thus a false indication of the water level within the gage will frequently result 25 in disaster. With my device such disasters are impossible owing to the fact that movement of the lever within the casing is positively controlled by the float, particular attention being called to the fact that all valves 30 or mechanism liable to become clogged are dispensed with and the single movable member of the device, to wit, the spindle 6, has only a single stuffing box connection through which it extends to the exterior of said casing, and thus friction is reduced to the minimum, as well as all points of leakage from 35 said casing, which casing it is understood, should be of sufficient strength to resist the highest steam pressure attainable. The hollow float 9, if desired, may contain air under 40 pressure, whereby greater buoyancy is attained, and, if desired, the spindle 6 may be provided with a counterbalance for the lever 8, which counterbalance can be mounted upon 45 the spindle 6 exterior of the casing.

From the foregoing it is apparent that the superintendent, or other official of a plant, can at all times inspect the condition of the water level maintained within the various boilers, and thus check up carelessness 50 of employees, which carelessness could not, under ordinary conditions, be ascertained, the effect of this permanent record being to render more efficient and careful regulation of feed water to boilers as well as to avoid 55 accidents.

I claim:

A safety gage for liquids having a steam-tight casing comprising a cylindrical well portion having a laterally disposed chamber 60 extending therefrom at its upper end, water inlet and return pipe connections in the ends of the chambered portion of the casing, a spindle journaled within the walls of the laterally extended chamber portion of said casing, 65 the spindle having one end extended therethrough, an oscillatory lever secured to the stem within the casing, a float disposed in the bottom well portion of the aforesaid casing, the float being pivotally connected to 70 the free end of the oscillatory lever, radial spring guides secured to the body of the float having their free ends adapted to engage the walls of the casing well portion whereby the lateral play of said float with relation to the 75 walls of the well is limited, an arm secured to the end of the spindle exterior of the aforesaid casing, a gage-casing secured to the exterior wall of the chamber extension, a motor-driven index card mounted in the 80 gage-casing, and a stylus-lever for the index card connected to the arm.

In testimony that I claim the foregoing I have hereunto set my hand at Milwaukee in the county of Milwaukee and State of Wis- 85 consin in the presence of two witnesses.

FREDERICK GETTELMAN.
